[57] ABSTRACT

A hydraulic energy translating device of the peripherally expansible working chamber type in which one side plate cooperating with the cam and rotor to form one end of the working chambers is secured in a fixed position by the housing. Another side plate is rotatably mounted in the housing and is movable to close the other end of the working chambers. The movable side plate is urged into closing relationship with the working chambers when fluid pressure is developed in the high pressure circuit and is moved away from the working chambers to permit exhausting thereof when the high pressure circuit is exhausted.

HYDRAULIC ENERGY TRANSLATING DEVICE

This invention relates to hydraulic energy translating devices and more particularly to hydraulic energy translating devices in which the working chambers are connected directly with the low pressure chambers when the high pressure circuit is exhausted.

The present invention is disclosed in a hydraulic wheel motor which is used to provide an auxiliary drive on the steerable wheels of a vehicle. This drive is generally used at low vehicle speeds in off highway operation. To permit more efficient operation of the vehicle at higher highway speeds it is desirable to interconnect the high pressure and low pressure side of the fluid motor when it is inoperable thus reducing fluid flow losses in the motor. The present invention permits the relatively free interchange of fluid between the high pressure working chambers and the low pressure exhaust chambers of a vane type motor by incorporating a movable side plate. The side plate is urged into abutment with the cam portion of the vane motor when the inlet or high pressure circuit is activated to provide a seal between the inlet and outlet expandible chambers of the vane motor. When the high pressure circuit is not operable the side plate is moved away from the cam member by pressure developed in the high pressure chambers to permit the free interchange of fluid between the inlet and outlet chambers of the vane motor.

It is an object of this invention to provide in an improved hydraulic energy translating device a vane type fluid unit having a cam member and a rotor member one of which is secured and the other is drivingly connected to a drive shaft and one side plate that is movable to prevent or permit the free interchange of fluid between the high pressure and low pressure chambers of the vane unit.

Another object of this invention is to provide in a hydraulic pump/motor having a fixed cam member and a rotatable rotor member drivingly connected to a drive shaft through a planetary gearing unit, a movable side plate selectively controlled by the high pressure circuit to prevent fluid communication between the high pressure and low pressure working chambers of the vane unit only when the high pressure circuit is pressurized.

These and other objects and advantages of the present invention will be more apparent from the following description and drawings in which:

FIG. 1 is a cross sectional elevational view of a hydraulic unit;

FIG. 2 is a cross sectional view taken along line 2-2 of FIG. 1; and

FIG. 3 is an end view showing the fluid passages in the hydraulic unit.

Referring to the drawings and particularly, FIG. 1, there is shown a hydraulic wheel motor generally designated 10 having a housing portion 12 integral with or otherwise secured to wheel mounting supports 14 and 16. The housing 12 has a pair of fluid supply passages 18 and 20 formed therein which communicate fluid to feed chambers 22 and 24, respectively. The passage 18 is also in fluid communication with a control chamber 26 formed by the housing 12 and a movable side plate 28. A ball check valve, generally designated 29, including a ball 30, a seat 32 formed in the housing 12 and a stop member 34 is disposed

between the passage 18 and the chamber 26. The ball check 29 permits the free flow of fluid from passage 18 to chamber 26, but prevents reverse flow from the chamber 26. The passage 18 is also in fluid communication via a passage 36 and a ball check generally designated 38 with an exhaust passage 40. The passage 20 is in fluid communication with the control chamber 26 through a ball check 42 similar in construction to ball check 29 and via passage 44 through ball check 46 with the exhaust passage 40. The ball check 42 permits free flow from passage 20 to chamber 26 but, prevents reverse flow. The feed chamber 22 is in fluid communication with a plurality of peripherally spaced chambers 48 through an annular passage 50 formed in a cam member 52. The feed chamber 24 is in fluid communication with a plurality of peripherally spaced chambers 54 via an annular passage 56 formed in the cam member 52.

20 The cam member 52 is secured in the housing 12 by an end cover 58 threaded in the housing 12 and positioned therein by a locking plate 60 and a fastener 62. The cam 52 is pinned to a ring gear 64 by a pin 66 which ring gear 64 is positioned against the cam 52 by the cover 58 and has an inwardly extending radial hub portion 68 forming a fixed side plate for the hydraulic unit 10.

25 The ring gear 64 is a member in a planetary gear set generally designated 70 which also includes a planet carrier 72 drivingly connected to a drive shaft 74 and rotatably mounting a plurality of pinion gears 76 which mesh with the ring gear 64 and a sun gear 78. The sun gear 78 has a circumferential extension which is 30 drivingly connected to a spline 80 on a rotor 82 which is rotatably mounted in the housing 12 circumjacent the cam 52 between the side plates 28 and 68. The sun gear 78 is rotatably mounted on the drive shaft 74 by a bushing 84 and the drive shaft 74 is rotatably mounted in the housing 12 in the cover 58 by roller bearings 86 and 88 respectively. The drive shaft 74 includes a mounting surface 90 adapted to receive a drive wheel and a plurality of fasteners 92 adapted to secure the drive wheel to the shaft 74.

35 The rotor 82 has a plurality of slots 94 each having a vane 96 slidably disposed therein which vanes 96 are extended radially outwardly by fluid pressure and centrifugal force into abutment with the inner surface of cam 52 to provide a plurality of fluid chambers such as 98 between the rotor 82 and the cam 52. The side plates 28 and 68 cooperate with the cam 52 and rotor 82 to close the ends of fluid chambers 98.

40 As seen in FIG. 2 the cam 52 has three lobes 100 which are adjacent the chambers 48 and 54. It will be appreciated that as the rotor 82 rotates, the chambers 98 will pass the chambers 48 and 54 to be filled with fluid at one chamber such as 48 and exhaust fluid at the other chamber such as 54 depending upon the rotational direction of the rotor 82. If, for example, high pressure fluid is supplied through passage 18 the chamber 48 will be pressurized thereby causing the rotor 52 to rotate in a clockwise direction, as viewed in FIG. 2, and the fluid in the chamber 98 adjacent chamber 54 will be directed to exhaust via passage 20. If fluid pressure is supplied via passage 20, the rotor 82 will locate in a counterclockwise direction.

When the passage 18 is pressurized fluid pressure will also be fed through ball check 29 to the control chamber 26 to move the side plate 28 into abutment with the cam 52 thereby cooperating with the vane members 96 to provide a seal between the adjacent chambers 98. The ball check 42 will prevent fluid flow from the chamber 26 to exhaust. The high pressure fluid in control chamber 26 will also be directed via passage 102 and annular groove 103 to the underside of the vanes 96 to urge them outward against the cam 52. Since it is virtually impossible to prevent some leakage from a rotating type vane motor such as that disclosed herein, the leakage fluid is directed via exhaust passage 40 through ball check 38 or 46 to the passage 18 and 20 respectively whichever of the passages 18 or 20 is operating as the low pressure passage at that moment. If both passages 18 and 20 are exhausted and fluid pressure is developed in the chambers 98 through the rotation of the rotor 52 being driven by the drive shaft 74 through the planetary gearing 70, the pressure so developed in the chambers 98 will move the side plate 28 axially relative to the drive shaft 74 away from the cam member 52 thereby permitting the free interchange of fluid between the chambers 98. When the side plate 28 has moved the pressure in chambers 98 will decrease substantially to reduce the flow losses in the motor 10.

The planetary gear set 70 is incorporated to provide a speed reduction between the rotor 82 and the drive shaft 74 when the wheel motor is being operated. The ring gear 64 is stationary, and therefore provides a reaction member, so that as the sun gear 78 is driven by the rotor 82, the carrier 72 will be driven at a reduced speed to drive the drive shaft 74.

Obviously, many modifications and variations of the present invention are possible in light of the above teachings. It is, therefore, to be understood that within the scope of the appended claims the invention may be practiced otherwise than as specifically described.

What is claimed is:

1. A hydraulic energy translating device comprising: a stationary housing; a cam member secured to said housing; a rotor member; vane means slidably disposed in said rotor member and being movable to abut said cam member to form a plurality of working chambers; shaft means drivingly connected with said rotor member; side plate means located in said housing for closing said working chambers including slidable side plate means slidably disposed in said housing means and being movable axially relative to said shaft means to selectively close the working chambers; control chamber means formed between said slidable side plate means and housing; first fluid passage means for selectively communicating fluid to and from said working chambers; second fluid passage means for selectively communicating fluid to and from said working chambers; control valve means in said first fluid passage means for directing fluid communicating to said control chamber means when said first fluid passage means is communicating fluid pressure to said working chambers; said slidable side plate means being moved to open said working chambers to permit free interchange of fluid between said first and second fluid passage means when said first and second fluid passage means are exhausted to prevent pressure development in said working chambers.

2. A hydraulic motor comprising: a stationary housing; cam means secured in said housing including fluid passages therein; a rotor rotatably mounted on said housing within said cam means; vane means slidably disposed in said rotor and being movable to abut said cam means to form a plurality of working chambers; sun gear means drivingly connected with said rotor; fixed side plate means located in said housing means abutting said cam means and said rotor to close one side of the working chambers; ring gear means secured to said fixed side plate means; carrier means having pinion gear means meshing with said sun and ring gear means; output drive shaft means drivingly connected with said carrier means; slidable side plate means slidably disposed in said housing means and being movable into and out of abutting relation with said cam means and said rotor to selectively close the other side of the working chambers and including feed passage means aligned with the inner end of said vane means in said rotor; control chamber means formed between said slidable side plate means and housing; first supply passage means for communicating high pressure fluid to and directing exhaust pressure fluid from one of said passages in said cam means; second supply passage means for communicating high pressure fluid to and directing exhaust pressure fluid from another of said passages in said cam means; first control valve means in said first passage means for directing fluid pressure to said control chamber means when said first supply passage means is pressurized and for preventing fluid communication from said control chamber means when said second supply passage means is pressurized; and second control valve means in said second supply passage means for directing fluid pressure to said control chamber means when said second supply passage means is pressurized and for preventing fluid communication from said control chamber means when said first supply passage means is pressurized; said slidable side plate means being moved out of abutment with said cam means and said rotor when both of said first and second supply passage means are exhausted to prevent pressure development in said working chambers.

3. A hydraulic energy translating device comprising: a stationary housing; cam means secured in said housing including fluid passages therein; a rotor rotatably mounted on said housing within said cam means; vane means slidably disposed in said rotor and being movable to abut said cam means to form a plurality of working chambers; a shaft member drivingly connected with said rotor; fixed side plate means located in said housing means abutting said cam means and said rotor to close one side of the working chambers; slidable side plate means slidably disposed in said housing and being movable into and out of abutting relation with said cam means and said rotor to selectively close the other side of the working chambers and including feed passage means aligned with the inner end of said vane means in said rotor; control chamber means formed between said slidable side plate means and housing; first supply passage means for communicating fluid to and from one of said passages in said cam means and to said working chamber means; second supply passage means for communicating fluid to and from another of said passages in said cam means and to said working chamber means; first control valve means in said first supply passage means for preventing fluid communicat-

ing from said control chamber means when the fluid pressure in said second supply passage means is higher than the fluid pressure in said first supply passage means; and second control valve means in said second supply passage means for preventing fluid communication from said control chamber means when the fluid pressure in said first supply passage means is higher than the fluid pressure in said second supply passage means; said slidable side plate means being moved out of abutment with said cam means and said rotor when both of said first and second supply passage means are exhausted to prevent pressure development in said working chambers.

4. A hydraulic energy translating device comprising: a stationary housing; cam means secured in said housing including fluid passages therein; a rotor rotatably mounted on said housing within said cam means; vane means slidably disposed in said rotor and being movable to abut said cam means to form a plurality of working chambers; a shaft member drivingly connected with said rotor; fixed side plate means located in said housing means abutting said cam means and said rotor to close one side of the working chambers; slidable side

plate means slidably disposed in said housing and being movable into and out of abutting relation with said cam means and said rotor to selectively close the other side of the working chambers and including feed passage means aligned with the inner end of said vane means in said rotor; control chamber means formed between said slidable side plate means and housing; first supply passage means for communicating fluid to and from one of said passages in said cam means and to said 10 working chamber means; second supply passage means for communicating fluid to and from another of said passages in said cam means and to said working chamber means; control valve means in one of said supply passage means for preventing fluid flow from 15 said control chamber means when the fluid pressure in the other of said supply passage means is higher than the fluid pressure in said one supply passage means; said slidable side plate means being moved axially out of abutment with said cam means and said rotor when 20 both of said first and second supply passage means are exhausted to prevent pressure development in said working chambers.
